SURF BOARD

Filed Nov. 9, 1929

Raymond M. Pollard

INVENTOR.

UNITED STATES PATENT OFFICE

RAYMOND McMILLEN POLLARD, OF LOS ANGELES, CALIFORNIA

SURF BOARD

Application filed November 9, 1929. Serial No. 405,868.

This invention relates to improvements in aquatic apparatus and more particularly to surf boards and the like.

One of the objects of this invention is to provide a simple, efficient and inexpensive surf board equipped with propulsion means effective in all cases where there is an incoming tide or in-rolling waves.

A further object thereof is to provide in combination with a surf board a blade designed when in collapsed or closed position on this board to float with the board in which case the board is propelled by the hands or feet of the occupant, but whenever the waves begin to move in a direction counter to the intended movement of the board the occupant can instantly open the blade and make it assume a perpendicular position beneath the surf board where the blade can be subject to the action of the waves and be automatically propelled towards the shore or beach without the intervention of the occupant.

A still further object thereof is to provide a hinged mounting for the propulsion blade so constructed and arranged upon the surf board that the hinges or hinged plates may be countersunk, at the same time, into a recess formed in the board for this purpose to assure that the blade when closed will overlap the under side of the board.

Another object of this invention is to hinge the propulsion blade in a manner to cause its inner end to contact the surf board for the purpose of projecting the blade in a perpendicular position relatively to the board to prevent the blade from swinging on an arc greater than 90 degrees.

With the above and other objects in view my invention consists in the combination, arrangement and details of construction disclosed in the drawings and specification and then more particularly pointed out in the appended claims.

In the drawings, wherein similar reference characters designate similar parts throughout the respective views,

Figure 1 is a top plan view of my invention,

Figure 2 is a side elevation thereof with the propulsion blade closed,

Figure 3 is a view similar to Figure 2 but showing the blade in open, operative position,

Figure 4 is a rear end elevation of my invention,

Figure 5 is a cross section taken thru a reinforcing rib of the blade, and

Figure 6 is a perspective view, partly broken away, showing the propulsion blade in open operative position, and

Figure 7 is a fragmental sectional detail view of a surf board showing my blade in fully open position perpendicularly arranged relatively to said board.

In the drawings, which are merely illustrative of my invention, 10 designates an aquatic device such as a surf board that is made rectangular in shape. The propulsion blade for said surf board is designated 11 being preferably of rectangular formation except that the blade is curved at its outer end as at 12. A pair of hinged plates 13 are secured by fasteners 12' to the inner face of the blade 11 and a fixed hinged plate 14 is secured by fasteners 15 in countersunk relation into the board 10.

The board 10 is also cut away as at 18 for the reception of the hinged plate 13 when the latter is in a fully closed position. It will be seen that the hinged collars 15' are also countersunk directly to the surf board 10, the pinte 16 passing through said collars and through the board 10.

The line of hinges or hinge collars 15' is substantially the medial line of the board 10. The correct position of this surf board at the time it is to be placed in the water is shown in Figure 2 where the surf blade 11 overlies the under side of the surf board in collapsed relationship. In this position of the parts the occupant may lie down upon the board and the board and blade will both float upon the surface of the water and the occupant may use his feet or hands to propel the board forwardly or rearwardly. The usual cruising range of this surf board is the area of the beach up to high wave line and when this point is reached and the

wave starts to come in, the occupant can take hold of the blade 11 and open it as far as it swings downwardly into the water and when the inner edge of the blade 11 engages the under side of the board, the blade can move 5 no further and occupies the perpendicular position shown in Figure 3. As the waves now roll in, they will engage the blade 11 and press it toward the front of the board, but as the blades can move no further, the 10 board itself is propelled by the waves without any physical exertion by the occupant of the board, so the waves will push the surf board back to the border of the beach at which time the blade can be closed again 15 to allow the surf board to float under direction of the occupant.

There cannot be any severe strain on the blade at any time nor on its hinges. The 20 blades may be reinforced by having the cross rib 17 secured transversely thereof. I do not mean to limit myself to the exact details of construction disclosed herein but intend to cover all variation falling within the 25 scope of the present claims.

What I desire to claim and secure by Letters Patent is:

1. A device as described consisting of a flat board, a hinged plate carried by said 30 board between its ends, means limiting the swinging movement of said hinged plate to a perpendicular position relatively to said board, said board having a pocket to receive said hinges when the plate is in close position and in overlying relationship upon the 35 board.

2. A device of the kind described consisting of a surf board, a propulsion plate, a plurality of hinges countersunk transversely 40 in said board in fixed relation, movable hinges normally countersunk in said board, and attached to the inner end of said propulsion plate and designed to permit the plate to open and to cause the inner end of the 45 plate to abut the fixed hinges to thereby cause the propulsion plate to assume a perpendicular position.

3. A surf board having a propulsion blade overlying the under side thereof so that as 50 the board floats the blade is in close position, means hingedly connecting the inner end of said blade to said board whereby the blade can be manually moved on its hinges until its inner edge overlies the board and the 55 blade assumes a perpendicular position and may be impinged by the action of the in-flow of waves.

4. A device as described consisting of a flat board, a pair of oppositely arranged 60 hinge plates, said board being cut away to receive in countersunk relation therein the opposite hinge plates including the hinge collars, and a propulsion blade secured to the movable hinge plate in such a manner that 65 when the movable hinge plate is counter-

sunk in the board the blade is in overlapping relation upon the under side of the board and such that when the blade is moved to a fully open position its inner edge will be stopped against further movement by contact with the board, the outer end of said propulsion blade being curved. 70

5. A device as described consisting of a surf board and a blade extending in overlying relationship thereupon, and means 75 whereby said blade can swing down out of contact with the board and assume a perpendicular position therebeneath to be engaged by waves for the self-propulsion of 80 the board, there being a transversely extending reinforcing rib mounted upon one side of the blade.

In witness whereof he has hereunder set his hand this nineteenth day of February, 1930.
